VARIABLE REACTANCE TRANSFORMER

Joseph Tyrner, Englewood, N. J., assignor to Air Reduction Company, Incorporated, New York, N. Y., a corporation of New York

Application August 15, 1940, Serial No. 352,680

10 Claims. (CL. 171—119)

The present invention relates to transformers of the type employing movable windings for varying their reactance.

An important object of the invention is flexibility of construction in such transformers enabling them to be readily manufactured to meet the requirements of different ampere ranges. Other objects of the invention are simplicity of construction and low cost of manufacture. It is an aim of the invention that its foregoing objects be accomplished by a transformer construction affording a wide range of reactance variation. A more specific object of the invention is to minimize the vibration or chattering inherent in the adjustment of the movable windings.

In accordance with the invention, a transformer construction is provided which comprises a pair of magnet members in form of rings disposed in axial alignment with one another, and two groups of magnet columns extending parallel to one another between the magnet rings. The two magnet column groups are disposed to successively alternate with one another circumferentially about the axis of the magnet rings. One of the two magnet column groups is embraced by two groups of transformer windings, one of which is made movable with respect to the other to vary the distance between the two transformer winding groups. This effects the desired reactance variation, a wide range of which is provided by the close spacing permitted between the two magnet column groups.

The foregoing transformer construction has the advantage of being readily adapted to different ampere ranges, by varying the size of the two magnet rings, which permits any desired number of magnet columns to be included in each of the two magnet column groups and consequently any desired number of transformer windings to be included in each of the two transformer winding groups.

The two magnet rings are carried by cylindrical supports of standard size, the mean diameter of the magnet rings being varied to suit the conditions desired. Each of these rings may conveniently be formed of a convolved band of magnetic material, which permits their outer diameter to be readily varied.

Each of the various magnet columns may comprise two rectangular legs set at an angle to one another to form the letter V in cross-section. When made in this manner, the various magnet columns are positioned so that the angle between the two legs of any magnet column diverges away

from the axis of the magnet rings. By proper choice of the angular setting of the two legs in each of the various magnet columns, a parallel spacing of the adjacent legs of any two adjacent magnet columns may be obtained. The total number of legs in said magnet columns is a multiple of four.

The two legs forming any of the various magnet columns may be made up of rectangular laminations of uniform size and provided with means common to both for securing them to one another and conjointly clamping together their respective laminations, a unitary structure being formed merely requiring a variation in the angle between the two legs to adapt it to the particular conditions desired.

The adjustment of the movable windings may be effected by the use of a threaded shaft journaled in the aforementioned supports for the magnet rings. Two nut-members may be provided on the threaded shaft in spaced relation to one another. The movable windings may be carried by a spider loosely surrounding the threaded shaft and supported by a plurality of rods movably extending through openings in the nut-members, which are urged toward one another by yieldable means operating with opposing forces on the supporting rods. Vibration or chattering in the adjustment of the movable windings is in this manner effectively minimized.

The invention will be understood from the following description taken in conjunction with the accompanying drawings in which Fig. 1 is a view in side elevation of an embodiment of the invention; Fig. 2 is a vertical section on the line 2—2 of Fig. 1, as seen from the right of that figure; and Figs. 3 and 4 are horizontal sections on the lines 3—3 and 4—4 of Fig. 1, as seen from the top and bottom of that figure, respectively.

Referring particularly to Figs. 1 and 2, upper and lower cylindrical castings 11 serve as the supports for upper and lower magnet rings 12. Each of the supporting castings 11 is provided with an inwardly projecting annular flange 11a; and each of the magnet rings 12 is constructed by winding a band of magnetic material on the flange 11a of its respective supporting casting 11. This construction of the two magnet rings 12 is facilitated by upper and lower annular guide plates 14 rigidly secured to the two supporting castings 11 around their annular flanges 11a, as by welding. The two magnet rings 12 contact with these guide plates, the outer diameter of which is purposely made large to permit varying

the outer diameter of the two magnet rings 12. The two bands of magnetic material forming the two magnet rings 12 may be prevented from uncoiling by welding their outer ends to the convolutions underneath. Suitable base members 15 are secured by welding or otherwise to the lower plate 14. Centrally mounted for rotation in the upper and lower castings 11 is a threaded shaft 16 provided with an upper operating hand-wheel 17.

The embodiment of the invention shown in the drawings comprises a total of six magnet columns 19, which are disposed at regular intervals about the axis of the shaft 16 and contact at their ends with the two magnet rings 12. As best shown in Figs. 3 and 4, each of the six magnet columns 19 comprises two rectangular legs 20 disposed at an angle to one another to form the letter V in cross-section, and is positioned so that the angle between the two legs 20 diverges away from the axis of the shaft 16. The angle between the two legs 20 is the same for each of the six magnet columns 19, and is such that the adjacent legs 20 of any two adjacent magnet columns 19 are parallelly spaced with respect to each other.

Each of the two legs 20 forming any of the six magnet columns 19 may be made up of rectangular laminations of the same size extending cross-wise to the longest cross-sectional leg dimension, as shown in Figs. 3 and 4, and held between inner and outer vertical angle members 21 and 22, respectively. Each of the six magnet columns 19 thus includes in its construction an inner pair of clamping members 21 and an outer pair of clamping members 22. The inner two members 21 may be rigidly connected to one another by welding them to a number of vertically aligned rod members 24, while the outer two members 22 may be rigidly connected to one another by welding them to a number of saddle-shaped members 25. Bolts 26 passing through the saddle-shaped members 25 serve to draw the two pairs of rigidly connected clamping members 21 and 22 toward one another. Each of the six magnet columns 19 thus constitutes a unitary structure capable of independent assembly. As shown in Fig. 2, the upper and lower rod members 24 included in this magnet column construction have nut-carrying threaded ends 24a which extend through holes in the magnet rings 12, the plates 14 and the upper and lower casting 11; whereby each of the six magnet columns 19 is held in place between the magnet rings 12, which are held against their adjacent plates 14 secured to the upper and lower castings 11.

The embodiment of the invention shown in the drawings comprises a total of six transformer windings consisting of three fixed windings 27 and three movable windings 28. As will be noted, the six windings are arranged in pairs alternately embracing three of the magnet columns 19, each pair consisting of a fixed winding 27 and a movable winding 28. The fixed windings 27 are preferably made larger than the movable windings to permit movement of the latter into and out of the transformer. Each of the six windings is substantially triangular-shaped with the view to minimizing the spacing between any two adjacent magnet columns 19.

As shown, the three fixed windings 27 are positioned around the uppermost portions of their embraced magnet columns 19. The means to support them in this position includes upper and lower clamping plates 29 and 30 between which they are firmly held at their inner portions by

bolts 31 passing through bosses 32 formed on the upper casting 11 and abutting the upper plates 29, and at their outer portions on bars 34 supported on tie-rods 35 hanging from the upper plate 14.

The three movable windings 28 are supported on a spider 36 loosely surrounding the shaft 16. The shape of this spider is shown in Fig. 4. It comprises a central portion 36a from which extend three pairs of complementary arms 36b and 36c. Each of the three movable windings 28 is partly carried by a pair of these arms 36b and 36c, to which it is secured by straps 37, while another strap 39 secures it to the central spider portion 36a.

Referring particularly to Fig. 2, the spider 36 is connected to the shaft 16 through a resilient mounting comprising three bolts 40 rigidly secured to the spider 36 at their lower ends. Spaced apart and threaded on the shaft 16 are two nut-members 41 provided with appropriate openings through which the bolts 40 pass freely so as to permit sliding movement, compression springs 42 being provided on the bolts 40 above the nut-members 41 and compression springs 44 being provided below the nut-members 41. The upper springs 42 exert upward forces on the bolts 40 and downward forces on the upper nut-member 41; while the lower springs 44 exert downward forces on the spider 36 and upward forces on the lower nut-member 41. This resilient mounting is thus effective in taking up any tendency of loose play between the nut-members 41 while at rest or in motion on the shaft 16, thereby insuring that the spider 36 may be operated in either direction of adjustment substantially without chattering or vibration. Preferably, the upper springs 42 are stronger than the lower springs 44 to compensate for the forces of repulsion exerted on the movable windings 28 by the fixed windings 27. As shown in Fig. 4, rotational displacement of the spider 36 by the rotation of the shaft 16 is prevented by a strip 45 of non-conducting material secured at its ends to two of the complementary spider arms 36b and 36c and adapted to freely ride on a fixed rod 46 mounted in the upper and lower plates 14.

In transformers of the type to which the present invention relates, the primaries are made of smaller wire than the secondaries. Therefore, in the embodiment of the invention shown in the drawings, it is preferred to use the movable windings 28 as the primaries and the fixed windings 27 as the secondaries. However, this is not essential, since it is possible to use the fixed windings 27 as the primaries and the movable windings 28 as the secondaries. Concerning the transformer flux established by the combined action of the various windings, it is apparent that it is made to travel in opposite directions through any two adjacent magnet columns 19.

From the foregoing description, it is clear that the movable windings 28 may be moved by the shaft 16 between the extreme positions in which they respectively surround the uppermost and lowermost portions of their embraced magnet columns 19. In their uppermost position, the movable windings 28 are completely disposed within the fixed windings 27, because of which the leakage flux is very low. By reason of the close spacing of the various magnet columns 19, the leakage flux nevertheless increases at a rapid rate as the movable windings 28 are moved out of the fixed windings 27 and attains a maximum of considerable value at the lowermost position

of the movable windings 28. It is apparent that the embodiment of the invention shown in the drawings provides for an exceptionally wide range of reactance variation.

Because of the large forces prevailing in transformers of the type to which the present invention relates, it has in general been found impracticable because of chattering hitherto to construct them for heavy current duty. In accordance with the invention, however, transformers of well over 400 ampere maximum current capacity may be obtained without difficulty.

The embodiment of the invention shown in the drawings may have its various windings connected in various ways depending on the use to which the transformer is applied. It may thus be used as a single phase transformer by parallel connection of its movable windings 28 (serving as primaries) to the source, and by parallel connection of its fixed windings 27 (serving as secondaries) to the load. As a 3-phase transformer, of course, its movable windings 28 (serving as primaries) may be Y or A connected to the source, while its fixed windings 27 (serving as secondaries) may be Y or A connected to the load.

It is to be understood that the invention is not limited to the particular embodiment shown in the drawings, which embodiment may be modified in various ways without departing from the spirit of the invention.

What is claimed is:

1. A transformer comprising a pair of magnet rings disposed in axial alignment with one another, a first group of magnet columns extending parallel to one another between said magnet rings, two groups of windings embracing said first group of magnet columns, a second group of magnet columns extending parallel to one another between said magnet rings, said two magnet column groups being disposed to successively alternate with one another about the axis of said magnet rings, each of the columns included in said two magnet column groups consisting of two rectangular legs set at an angle to one another to form the letter V in cross-section and being positioned to cause said angle to diverge away from the axis of said magnet rings, and means for varying the distance between said two winding groups.

2. A transformer comprising a pair of magnet rings disposed in axial alignment with one another, a first group of magnet columns extending parallel to one another between said magnet rings, said two magnet column groups being disposed to successively alternate with one another about the axis of said magnet rings, each of the columns included in said two magnet column groups consisting of two rectangular legs set at an angle to one another to form the letter V in cross-section and being positioned to cause said angle to diverge away from the axis of said magnet rings, said angle being chosen to cause the adjacent legs of any two adjacent magnet columns to be spaced parallel from one another, and means for varying the distance between said two winding groups.

3. In a transformer construction, the combination with a movable winding of a means for moving said winding comprising a threaded shaft, two nut-members disposed on said shaft,

in spaced relation to one another, a plurality of bolts supporting said winding and movably extending through openings in said nut-members, and yieldable means operating with opposing forces on said bolts and urging said nut-members toward one another.

4. In a transformer construction, the combination with movable windings of a means for moving said windings comprising a threaded shaft, two nut-members disposed on said shaft in spaced relation to one another, a supporting spider for said windings loosely surrounding said shaft, a plurality of bolts connected to said spider and movably extending through openings in said nut-members, and yieldable means operating with opposing forces on said bolts and urging said nut-members toward one another.

5. In a transformer construction, the combination with a first winding and a second winding of a means for moving said first winding toward and away from said second winding, said means comprising a threaded shaft, two nut-members disposed on said shaft in spaced relation to one another, a plurality of bolts supporting said first winding and movably extending through openings in said nut-members, and yieldable means operating with opposing forces on said bolts and urging said nut-members toward one another, said yieldable means operating on said bolts with a less force in the direction of motion of said first winding toward said second winding than in the direction of motion of said first winding away from said second winding.

6. A transformer comprising two magnet rings spaced apart and disposed in axial alignment with one another, magnet columns having pairs of legs to a total number which is a multiple of four all of which are secured in a circular arrangement between and abutting said magnet rings, pairs of windings surrounding alternate pairs of legs of said magnet columns, and means for simultaneously varying the distance between the windings of each pair of windings.

7. A transformer comprising a pair of magnet rings disposed in axial alignment with one another, magnet columns having pairs of legs to a total number which is a multiple of four all of which are secured in a circular arrangement between and abutting said magnet rings, pairs of windings surrounding alternate pairs of legs of said magnet columns, a winding of each pair being capable of nesting within the other winding of that pair, and means for simultaneously varying the distance between the windings of each pair of windings.

8. A transformer comprising a pair of magnet rings disposed in axial alignment with one another, a plurality of magnet columns all secured in a circular arrangement about the axis of said magnet rings and parallel to one another between said magnet rings, a group of windings embracing alternate magnet columns, another group of windings embracing the same alternate magnet columns, and means for varying the distance between said two groups of windings.

9. A transformer comprising a pair of magnet rings disposed in axial alignment with one another, a plurality of magnet columns all secured in a circular arrangement about the axis of said magnet rings and parallel to one another between said magnet rings, the said magnet rings and magnet columns being each laminated so that all of the laminations of both the magnet rings and the magnet columns lie in substantially cylindrical planes about said axis, a group of wind-

ings embracing alternate magnet columns, another group of windings embracing the same alternate magnet columns, and means for varying the distance between said two groups of windings.

10. A transformer comprising a pair of magnet rings disposed in axial alignment with one another and each formed of a convolved band of magnetic material, a plurality of magnet columns each longitudinally laminated so that all of 10 its laminations are substantially parallel to the

5 laminations of said magnet rings, all of said magnet columns being secured in a circular arrangement about the axis of said magnet rings and parallel to one another between said magnet rings, a group of windings embracing alternate magnet columns, another group of windings embracing the same alternate magnet columns, and means for varying the distance between the two groups of windings.

JOSEPH TYRNER.
